AXLE AND FENDERS UNIT

Ewen Butcher, 682 Kirk Ave., Ventura, Calif. 93003

Filed Aug. 17, 1971, Ser. No. 172,610

Term of patent 14 years

Int. Cl. D12—16
U.S. Cl. D14—2

FIG. 2

FIG. 1

FIG. 3

FIG. 5

FIG. 4

FIG. 1 is a perspective view of an axle and fenders unit showing my new design;

FIG. 2 is a top plan view thereof;

FIG. 3 is a bottom plan view thereof;

FIG. 4 is a side elevational view thereof, showing the side opposite that shown in FIG. 1; and,

FIG. 5 is a front elevational view thereof.

I claim:

The ornamental design for an axle and fenders unit, substantially as shown.
